(57) CLAIM

The ornamental design for a transparent air freshener disperser with a decorative insert, as shown and described.

DESCRIPTION

FIG. 1 is a front perspective view of the transparent air freshener disperser with a decorative insert showing my new design;

FIG. 2 is a front view thereof, the rear and side views being identical to that shown;

FIG. 3 is a top view thereof;

FIG. 4 is a bottom view thereof; and,

FIG. 5 is a front perspective view of the decorative insert portion of the design shown separately for clarity of illustration.
